Patented Aug. 12, 1958

183,366

PHONOGRAPH PICKUP ARM

Joseph Palma, Jr., Wheaton, Ill., assignor to Shure
Brothers Incorporated, Evanston, Ill., a corporation of
Illinois

Application December 17, 1957, Serial No. 48,929

Term of patent 14 years

(Cl. D26—14)

Fig. 3

Fig. 4

Fig. 5

Fig. 1 is a perspective view of a phonograph pickup arm, showing my new design;

Fig. 2 is a side elevational view, the opposite side being substantially a mirror image thereof;

Fig. 3 is a top plan view;

Fig. 4 is a rear elevational view; and

Fig. 5 is a front elevational view thereof.

The dominant features of my new design are shown in solid lines in the drawing.

I claim:

The ornamental design for a phonograph pickup arm, substantially as shown and described.
